(57) **CLAIM**

The ornamental design for a bottle, as shown and described.

DESCRIPTION

FIG. 1 is a perspective view of a first embodiment of a bottle, showing my new design;

FIG. 2 is a front, elevation view thereof;

FIG. 3 is a rear, elevation view thereof;

FIG. 4 is a right, elevation view thereof;

FIG. 5 is a left, elevation view thereof;

FIG. 6 is a top, plan view thereof;

FIG. 7 is a bottom, plan view thereof;

FIG. 8 is a closeup, partial, side view thereof, showing knurling of the cap of the bottle;

FIG. 9 is a perspective view of a second embodiment of a bottle, showing my new design;

FIG. 10 is a front, elevation view thereof;

FIG. 11 is a rear, elevation view thereof;

FIG. 12 is a right, elevation view thereof;

FIG. 13 is a left, elevation view thereof;

FIG. 14 is a top, plan view thereof;

FIG. 15 is a bottom, plan view thereof; and,

FIG. 16 is a closeup, partial, side view thereof, showing knurling of the cap of the bottle.

The broken lines in FIGS. 1, 4, 6, 7, 9, 12, 14, and 15 are for the sole purpose of showing portions of the bottle, and do not form a part of the claimed design.

1 Claim, 12 Drawing Sheets
